ATTORNEY

John B. Miller
WITNESS:

UNITED STATES PATENT OFFICE

ROY HENDRIX, OF SOUTH CARROLLTON, KENTUCKY

PORCH SWING

Application filed May 31, 1929. Serial No. 367,463.

This invention relates to a swing for use on porches and the like, the general object of the invention being to provide a swing of great strength and which can be manufactured to sell at low cost and one in which the back can be adjusted to various positions to suit the desires of the user.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is a front view of the swing.
Figure 2 is an end view thereof.
Figure 3 is a top plan view.

Figure 4 is a view of the member for holding the back rod in adjusted position.

In these views, the numeral 1 indicates a front part of a bottom frame, and the numeral 2 the end pieces of the frame. Strips or slats 3 have their ends connected with the end pieces 2 to form the seat portion of the swing. Vertically arranged slats 4 have their lower ends secured to the end pieces and the upper ends of these slats are connected with the bars 5, the slats and bars forming the ends of the seat portion of the swing. A strip 6 is fastened to the upper edge of each bar 5 and forms an arm rest. I prefer to connect the ends of the end slats 4 to the pieces 2 and 5 by the bolts 7 to strengthen the structure. As shown, the bars 5 extend a considerable distance in rear of the seat of the swing and these extensions are each formed with a plurality of holes 8.

The back A of the swing is formed of the pair of bars 9 and the slats 10 which have their ends secured to the bars 9 and the lower ends of these bars are pivotally connected by the rear bolts 7 to the rear ends of the pieces 2, so that the back can be swung into various positions with respect to the seat part of the swing. This back is arranged between the extensions of the beams 5 and is supported

in adjusted position by a rod 11 which has its ends passing through any desired pair of holes 8 in the beams, so that the back will rest against said rod. Hook-shaped members 12 are passed through holes in the ends of the rod to hold the rod in place, the hook parts of these members fitting over the beams 5, as shown.

U bolts 13 are fastened to the ends of the beam 5 to receive the chains 14 which suspend the swing from the porch ceiling or other support.

Thus I have provided a swing of simple and inexpensive construction and of considerable strength and one in which the back can be adjusted to various inclined positions.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A porch swing comprising a seat, a plurality of spaced slats secured at their lower ends to the seat, horizontally disposed bars connecting the upper ends of the slats and extending rearwardly of and in a plane above the seat and having a plurality of relatively spaced openings in the portions thereof that project beyond the seat, a back rest pivoted to the seat and inclining upwardly therefrom between said bars, a rod extending through a pair of said openings in the bars, and having apertures in its ends and locking members extending through the apertures and having their upper portions bent at right angles and downwardly to form hook-shaped portions adapted to engage over the upper edges of the bars.

In testimony whereof I affix my signature.
ROY HENDRIX.
